Primary Examiner — Sandra Snapp

CLAIM

The ornamental design for a dispenser, as shown and described.

DESCRIPTION

FIG. 1 is an isometric view of a front, top, and left side of an ornamental design for a dispenser;

FIG. 2 is a front elevational view of the dispenser of FIG. 1; FIG. 3 is a rear elevational view of the dispenser of FIG. 1; FIG. 4 is a left side elevational view of the dispenser of FIG. 1, wherein the right side elevational view is a mirror image of the left side elevational view;

FIG. 5 is a top plan view of the dispenser of FIG. 1;

FIG. 6 is a bottom plan view of the dispenser of FIG. 1; FIG. 7 is an isometric view of a front, top, and left side of another embodiment of an ornamental design for a dispenser; FIG. 8 is a front elevational view of the dispenser of FIG. 7; FIG. 9 is a rear elevational view of the dispenser of FIG. 7; FIG. 10 is a left side elevational view of the dispenser of FIG. 7, wherein the right side elevational view is a mirror image of the left side elevational view;

FIG. 11 is a top plan view of the dispenser of FIG. 7; and, FIG. 12 is a bottom plan view of the dispenser of FIG. 7.

The broken lines in the drawings depict environmental subject matter only and form no part of the claimed design.
